UNITED STATES PATENT OFFICE

LEON E. LA BOMBARD, OF WEST NEWTON, MASSACHUSETTS, ASSIGNOR TO SPECIALTY AUTOMATIC MACHINE COMPANY, OF CHELSEA, MASSACHUSETTS, A CORPORATION OF MASSACHUSETTS

PACKAGE OF ROLLED SHEETS

Application filed November 8, 1927. Serial No. 231,846.

This invention relates to the production of collections or packages of cut sheets adapted to be removed singly for use, and has particular reference to such packages of 5 sheets of waxed wrapping paper.

Thin waxed paper is extensively used for wrapping articles for household uses, especially lunches and many articles of food both cooked and uncooked. A well-known 10 method of supplying such sheets to users is to make rolls of cut sheets wound or wrapped around a central core and enclosed in a wrapper or box. Separation of single sheets from a roll of them is not easy to 15 effect without more or less disarrangement or mussing of the remaining sheets, this difficulty being greater when the roll includes more than two or three dozens of the sheets. This difficulty is due to the thinness of the 20 sheets and the slippery nature of the waxy surfaces thereof. Another objection is that the roll of sheets must be un-rolled and re-rolled each time one or more of the sheets is or are removed, this being very inconvenient. Moreover if the entire number of 25 rolled sheets are removed from the central core and kept flat for the sake of convenience of access, the removed sheets are left loose and without any protection.

Another method of packaging cut sheets is in folded form in envelopes of paper or cardboard. An objection to this method of packaging is that the envelope must be opened and the desired sheets fumbled for 30 and withdrawn, frequently with the result that more than one sheet comes out when only one is wanted.

The object of the present invention is to furnish cut sheets of waxed wrapping paper, 40 which sheets are not only assembled in an economical manner but are easily separable, individually, for use, without rumpling or otherwise disturbing the rest of the sheets even if the assembly includes one hundred 45 or more of the sheets.

The above and other objects are accomplished by rolling any desired number of the sheets completely and successively one upon another and so confining the entire 50 roll that the sheets may be drawn out singly

from an end of the roll, each withdrawn sheet being the inner one, such withdrawal having no effect on the sheet next outside of the one so drawn out.

My invention consists in the package or 55 collection of sheets and the method of producing the same substantially as hereinafter described and claimed.

Of the accompanying drawings:—

Figure 1 is a side elevation, partly in section, of a core or mandrel suitable for use 60 in making the roll.

Figure 2 represents a section on line 2—2 of Figure 1, on a larger scale.

Figure 3 is a side elevation, partly in section, of a completed package.

Figure 4 represents a section on line 4—4 of Figure 3, on a larger scale than Figure 3.

In carrying out my invention I use a suitable core or mandrel 5, preferably collapsible, on which the desired number of sheets *a* are wound, each sheet being completely wrapped around the mandrel before winding of the next sheet begins, the result being that the edges of the sheets do not overlap but meet or are opposed to each other edge to edge with more or less space between said edges as indicated at *x* in Figures 2 and 4. In said figures the sheets are indicated by single lines with spaces between 70 the layers, in the interest of clearness of illustration. In practice, of course, there are no spaces between the superimposed coils or layers, and usually many more sheets are included than are illustrated in the drawings. 75

When the mandrel is a part of the machine which is employed for effecting the winding, said mandrel may be rotated by suitable gearing meshing with a pinion 6 at 80 one end of it. And said mandrel may be of any well-known collapsible type. For present purposes it is sufficient to illustrate the mandrel as of sufficiently thin metal or other material to enable it to collapse to facilitate its withdrawal endwise from the completed collection of sheets mounted thereon as will now be described.

After the required number of sheets *a* have been wound on the mandrel, each sheet 100

being completely wound before winding of the next one begins, both the mandrel and the sheets are inserted in a tube *b*, usually of pasteboard, and the mandrel is then slid out, leaving the article or package as illustrated by Figures 3 and 4. The only reason for employing a mandrel which can be collapsed is to render it easier to slip it out of the coiled sheets leaving the latter in the tube. It is customary, of course, to enclose the tube and its contained sheets in a paper wrapper for storage, transportation, and sale.

Owing to the fact that no edge portion of any sheet is in between two layers or coils of another sheet, that is, no sheet is interwound with another sheet, the innermost one and each succeeding innermost one, is easily removable through one end of the tube without starting another sheet out. A user can simply insert a finger, and by a slight pressure against the inner surface of the inner coil and an accompanying outward pulling action, start the inner sheet out far enough to be able to grasp it between two fingers and pull that sheet completely out. This action tends to convert the inner sheet temporarily into a form resembling a spirally coiled strip such as often used for a lamp lighter, reducing the diameter of the coils of the inner sheet slightly so that it easily leaves the next surrounding sheet and can be slid out. Afterwards the next inner sheet can be similarly removed.

While I have illustrated a tube as the confiner for the collection of sheets, I do not limit myself thereto. For instance, the confiner might be an elongated box having an end to be opened when a sheet is to be withdrawn. Such a box takes the place not only of the tube but also the wrapping which would usually be necessary to protect the whole for storage, shipping and exhibition for sale.

A particular advantage possessed by my improved package is that whether the roll of sheets be confined in a tube or box such as described, such tube or box can be placed on a shelf with the end through which the sheets are to be removed at the front of the shelf so that whenever a sheet is desired the removal can be effected by the fingers of only one hand.

An important advantage is that the sheets are always in sanitary condition for use. In practice the sheets are rolled and located in the container by machinery and are not touched by human hands. And then when the roll of sheets is confined in a box, no dust can gain access thereto. It is to be understood, of course, that when the roll is contained in a tube, end caps or closures of any suitable type will be employed.

Having now described my invention, I claim:—

1. A package comprising a container and a single roll therein, said roll comprising a plurality of sheets, each of said sheets being in the form of a complete coil free from intercoiling with any other sheet. 70

2. A package comprising a single roll, said roll comprising a plurality of sheets each of which is coiled completely and independently of the others and having no portion interposed between portions of other coiled sheets, and a confiner for said coiled sheets. 75

3. A package of separately removable 80 sheets of paper, comprising a container and a plurality of sheets therein, each of said sheets comprising a complete coil free from intercoiling with any other sheet, and the container having an end outlet for permitting the removal of sheets therethrough. 85

In testimony whereof I have affixed my signature.

LEON E. LA BOMBARD.
